No. 884,370.

PATENTED APR. 14, 1908.

H. E. DOBSON.

LIQUID DEPTH GAGE

APPLICATION FILED OCT. 11, 1907

UNITED STATES PATENT OFFICE

HARRY E. DOBSON, OF NEW YORK, N. Y.

LIQUID-DEPTH GAGE.

No. 884,370.

Specification of Letters Patent. Patented April 14, 1898.

Application filed October 11, 1907. Serial No. 396,990.

To all whom it may concern:

Be it known that I, HARRY E. DOBSON, a citizen of the United States, and a resident of Manhattan borough, New York city, in the county of New York and State of New York, have invented certain new and useful Improvements in Liquid-Depth Gages, of which the following is a specification.

This invention relates to liquid depth gages, and it consists in providing a float with a suitable guide and binding device so that when the gage is vertically placed in a liquid contained by a vessel, like a barrel or tank, and to the bottom of the vessel, the float will rise to the level of the liquid therein, and will be held in that position by the binder to the guide, so that when the gage is withdrawn from the vessel, the depth (and consequently the quantity) of the liquid can be ascertained and indicated by a scale on the guide with which the latter is provided, and with which the float registers.

The object of the invention, is to enable a person to quickly determine the liquid contents of a vessel of any sort having an opening at the top through which the gage can be inserted and placed vertically in the liquid and against the bottom of the vessel.

The nature and objects of the invention, will be more fully described in the following specification, and especially pointed out in the claims, taken in connection with the accompanying drawings which form a part of the specification and in which, similar letters refer to similar parts throughout the several views.

In the drawings:—Figure 1, represents the gage in front elevation and in position in a vessel containing a liquid, and of which a portion is shown in section that the operation of gage can be better understood. Fig. 2, is a front elevation of the gage with the float held in a fixed position to which it was elevated when it was put down into the vessel and its liquid contents, as seen in Fig. 1. Fig. 3, is a vertical section of the gage showing its interior construction and the crankshaped binder rod which binds the float to the inner wall of the guide tube when manipulated by means of the lever mechanism on top of the gage. Fig. 4, is a top view of the binder rod lever and cap of the guide. Fig. 5, is a modification of the parts shown in Fig. 4, by the addition of a spring secured to the binder rod lever which gives a spring pressure of the binder rod on the float. Fig. 6, is a hori-

zontal cross section of the guide tube and binder rod and top view of the float, showing the float pressed against the wall of the guide tube by the binder rod. Fig. 7, is a cross section of the guide tube and binder rod and top view of the float when free to move up and down within the tube clear of the wall of the latter and as ready for using the gage. Fig. 8, is a front view of the sleeve portion of the binder lever, and Fig. 9, is a top view of the lever. Fig. 10, is a vertical section of modified form of the float, as when made of a hollow metallic construction, or the like.

In the drawings:—A, represents the float; B, the guide in the form of a tube; and C, the binder rod, which are the essential members of the invention. The float may be of any substance of relatively lighter specific gravity than that of the liquids that are to be measured by the gage, such as cork, wood or the like; or else of metal, glass, or similar materials, when made in the hollow form seen in Fig. 10. The float A, is provided with a perforation A', in its vertical axis through which the binder rod C, is loosely fitted, that the float may freely slide vertically thereon, and the float is also of smaller diameter than that of the inside of the tube, B, that it may freely move up and down within the tube, when the binder rod is central within the tube. The binder rod C, is provided with cranks C', C'', at its ends and integral therewith, and the axes of which are eccentrically located from the axis of the tube B, by being trunnioned in corresponding positions and bearings in the cap B', and bottom B'', of the tube B, respectively, which are provided with such positioned bearings. In the bottom B'', the rod bearing is simply a hole B'', in which the lower crank journal C'', of the rod C, is fitted; but the upper crank journal C', is provided with sleeve D, which is fitted in the corresponding hole E, in the cap B', of the tube B, and the axis of which hole is in line with that of the corresponding hole in the bottom B'', when the cap is properly adjusted on the tube B. The sleeve D, is of oblong shape at its upper end D' and fitted to a correspondingly shaped opening F, in the crank lever F', having the knob F'', by means of which the lever and rod C, may be actuated, when desired. The lower portion D', of the sleeve D, has a slot D'', across its surface, like that in a screw head and into which the crank portion C', of the binder rod C, fits so that when the sleeve is rotated

in the cap B' , by the lever F' , it will carry the rod with it, thus causing the rod to press the float A , against the wall of the tube, B , so as to hold it in a fixed position therein. The cap B' , is internally threaded to fit the threaded end portion B^3 , of the tube and thereby secure it thereto, and is provided with a screw G , fitted thereto and which passes through a corresponding hole B^4 , in the wall of the tube B , to keep the crank bearing of the rod C , in true axial line with the crank bearing in the bottom B^2 , when the cap is adjusted on the tube. The cap is made in this way that the parts may be separable, and the float and rod removable from the tube. The rod C , is flexible on account of its slenderness, but excessive rotation within the tube is prevented by means of limiting pins H , H' which are secured in the cap for this purpose and which limit the sweep of the lever F' in each direction to the proper extent. The upper end C^6 , of the rod C , is threaded to fit the nuts I , I' , which when screwed down thereon with the sleeve D , and lever F' , in position thereon,—cause the crank portion C' , of the rod, C , to become drawn upwardly against the sleeve and the latter with the lever against the lower nut I , and thus binding the parts securely together, the top nut I' , merely serving as a check-nut against any possible accidental unscrewing of the parts, or loosening of the connections. This construction also gives a firm and secure hold of the lever mechanism on the binder rod when the parts are fastened together, while admitting of their being separated, when required.

A spring J , is shown as secured to the lever E' , in Fig. 5, and its free end J' , being in contact with the limiting pin H^2 , in the cap B' , which arrangement gives a spring tension in one direction of the rod C , against the float A , and pressing the latter against tube, sidewise. When the spring is attached to the lever in this way, the lever is held backwardly against the spring by the thumb of the user of the device who holds the tube in the hand with the fingers around it and the thumb on top of the knob holding the lever back with the thumb, and the cap uppermost. In this position, the gage can be then placed in the vessel V , and its liquid contents X , against the bottom V' , of the vessel. The main portion of the rod C , will then be central within the tube, and the float can rise upwardly by the buoyancy of the liquid upon the float to the surface level X' , of the liquid and then when at rest the thumb releases the spring pressure on the lever, and the latter presses the rod, and float against the tube and holds it there, and the gage can be withdrawn from the vessel and the depth of the liquid therein, ascertained by noting the position of the float with reference to the bottom of the tube, and indi-

cated on the scale K , which is graduated on the outside of the tube B , for the purpose, the lower edge A^2 , of the float registering with the graduation marks, and being visible through the slit L , which extends nearly the entire length of the tube. The bottom A^3 , of the float is made convex, to compensate for its weight and displacement of the liquid, so the registering edge A^2 , will be on the top level of the liquid, and thus indicate the latter when the gage is withdrawn from the vessel and examined.

The lever F' , is shown in Figs. 1, 2, 3 and 4, as bearing only against the outer portion B^5 , of the surface of the cap B' , and thereby giving a spring tension bearing down against the cap so that when the device is made in that manner, (that is, without the spring member J , seen in Fig. 5,) the lever is moved into position in either direction by the thumb alone, and the friction of the lever against the cap being sufficient to hold the parts in place and the float against the tube, as already explained. The spring principle shown in Fig. 5, can also be applied to the bottom end of the rod as well as to the top end, by a suitable lever and spring construction, practically of the same or similar design, as can be understood; and the bottom B^2 , can be detachably secured to the guide B , by the screw G' .

The particular form of construction shown and described in the drawings and specification, can be modified, as can be understood, without departing from the scope of this invention; therefore the float, the guide, and the float binding member, can be made in other ways than in the form shown, to meet any special applications required. The parts can be made of any suitable materials other than of metal, as is represented in the drawings, and which can also be understood. The gage can be of any suitable length or dimensions, needed to gage liquids in barrels, tanks, and other liquid containers.

While the tube B , serves to guide the float in its movement vertically therein, and provides for the registering scale thereon to indicate the position of the float when the device is used; it can also be seen that the rod C , acts as a guide for the float in its movement thereon; and that the tube and rod taken together and combined, form the binder mechanism complete.

From the foregoing description, the operation of the invention can be understood without further explanation, as it is only necessary to insert the gage vertically and downwardly, into the vessel and the liquid to be gaged, until the bottom of the gage rests on the bottom of the vessel, while holding the device in hand with the thumb resting on the cap against the lever knob which controls the binding rod, and keeping the latter central in the tube until the float rises to the level of

the liquid, and which enters the tube through the slit in the latter and through openings in the bottom of the tube of which one is shown sectionally in Fig. 3, at M. The lever is then 5 pushed around with the thumb, until the rod presses the float against the side of the tube which thereby holds it there fixedly, on account of the friction of the lever against the top of the cap. Or if provided with the 10 spring seen in Fig. 5, the tension of the spring will continue the pressure of the rod against the wall of the tube, when the lever is released by the thumb, and the binding effect of the rod on the float and tube thus secured. 15 The gage can then be taken out the liquid and vessel, and the depth of the liquid in the latter will be indicated by the distance of the float from the bottom of the gage, and by the register of the float with the scale graduations. 20 As the gage is taken out of the liquid, whatever amount of the latter remains in the tube will quickly run back into the vessel through the slit in the tube and the holes in the bottom of it, thus leaving it free from the 25 liquid excepting that which adheres to gage which can be wiped or dried off, and which can be disregarded.

From the foregoing description, it can be seen that I provide a simple and complete device, and that it meets all the requirements of such an article.

Having thus described my invention, what I claim, and desire to secure by Letters Patent, is:—

35 1. In a liquid depth gage, the combination of a float, a tubular guide incasing the float and having a float observing slit and a graduated scale, and a binder rod connected with the guide and passing through the float 40 and adapted to bind the float against the wall of the guide, substantially as described.

2. In a liquid depth gage, the combination of a float having a hole through its axis,

a tubular guide incasing the float and provided with a float observing slit and graduated scale, and a binder rod passing through the hole in the float and its ends crank shaped and trunnioned in the end members of the guide and one end of which rod is provided with an actuating lever and sleeve 50 mechanism by which the float can be pressed fixedly against the inner wall of the guide, substantially as described. 45

3. In a liquid depth gage, the combination of a cylindrical float having a hole 55 through its axis, a tubular guide incasing the float and provided with a float observing slit and graduated scale a bottom member and detachable cap member, and a binder rod having its ends crank shaped and trunnioned 60 in the bottom and cap members of the guide and its body portion extending through the hole in the float, substantially as described.

4. In a liquid depth gage, the combination of a float, a guide, and a binder rod connected with the float and guide and provided with a spring tension lever mechanism by which it can be actuated and the float can 65 be held fixedly at different positions along the guide, substantially as described. 70

5. A float rod binder for a liquid depth gage, consisting of the body portion C, and crank end portions C', C'', the slotted sleeve D, and actuating lever F', substantially as 75 described.

6. A liquid depth gage, consisting of the float A, the guide tube B, rod C, and lever F', combined and constructed substantially as described.

Signed at New York city, in the county of 80 New York and State of New York, this 7th day of October A. D. 1907.
